(57) **CLAIM**

The ornamental design for a dishwasher accessory, as shown and described.

DESCRIPTION

FIG. 1 is a front, top perspective view of a dishwasher accessory showing the new design;

FIG. 2 is a rear, top perspective view thereof;

FIG. 3 is a top view thereof;

FIG. 4 is a bottom view thereof;

FIG. 5 is a front view thereof;

FIG. 6 is a rear view thereof;

FIG. 7 is a right side view thereof;

FIG. 8 is a left side view thereof; and,

FIG. 9 is another perspective view of FIG. 1, showing an example environment.

The broken lines shown in the drawings illustrate portions of the dishwasher accessory and form not part of the claimed design. The broken lines shown in FIG. 9 illustrate environmental structure and form no part of the claimed design.

1 Claim, 7 Drawing Sheets
